SLUSH PUMP VALVE COVER
Raymond A. Pangburn, P.O. Box 94364,
Oklahoma City, Okla.
Filed Aug. 12, 1964, Ser. No. 389,003
5 Claims. (Cl. 220—55)

The present invention relates to pumps and more particularly to an improved valve cover or cap for slush pumps.

The present invention is an improvement over my co-pending application for Slush Pump Valve Cover, filed in the United States Patent Office July 27, 1964, under Serial Number 383,459.

Slush pumps of relatively large capacity are conventional equipment in oil well drilling and are used for circulating the drilling fluid. These pumps have generally cylindrical shaped upwardly open intake and exhaust fluid transferring bodies, commonly called "valve pots" which are respectively equipped with fluid intake and exhaust valves. The valve pots must be provided with means permitting access to the valve therein to service the valve. To accomplish this a cap or cover is usually provided at the upwardly disposed end of each valve pot which is usually attached to the valve pot by a plurality of stud bolts or bolts and nuts. A recent improvement comprises a ring or disk-like cap which is threadedly secured to the valve pot by a single plug member. This single member frequently works loose during operation of the pump resulting in malfunction of the associated valve. Furthermore, the type of cover in which a plurality of bolts holds the cover in place requires time to remove and replace each cap or cover resulting in extensive shut down time.

It is, therefore, the principal object of the invention to provide an improved replaceable valve cover or cap for a slush pump valve pot.

Another object is to provide a valve cover or cap which employs a single bolt and nut which is connected in a novel manner with each respective valve pot body.

Still another object is to provide a device of this class which employs a plurality of segmental cover locking members which are wedged within a recess formed in the valve cover cap.

Yet another object is to provide a device of this class which may be connected with existing slush pump valve pots without modification thereof and may be incorporated in the design of valve pots to be manufactured.

The present invention accomplishes these and other objects by connecting a valve cover receiving ring to the upwardly open end of a valve pot. Bolt and nut means, secured to the valve cover, cooperate with the ring in wedging cover lock members against the valve pot plug.

Other objects will be apparent from the following description when taken in conjunction with the accompanying single sheet of drawings, wherein:

FIGURE 1 is a fragmentary perspective view of a conventional slush pump illustrating, by solid lines, the relative position of one of the devices of the present invention when installed thereon;

FIGURE 2 is a top view, to a larger scale, of the device when installed on the pump;

FIGURE 3 is a vertical cross-sectional view taken substantially along the line 3—3 of FIG. 2; and,

FIGURE 4 is a vertical cross-sectional view, to a different scale, of a valve pot, per se, modified or constructed to coact with the present invention.

Like characters of reference designate like parts in those figures of the drawings in which they occur.

In the drawings:

The reference numeral 10 indicates a fragment of a conventional slush pump having a plurality of generally

2

cylindrical shaped bodies or valve pots, indicated at 12, respectively housing fluid intake and exhaust valves. One type of conventional removable valve pot cover or cap is indicated at 14.

5 Referring more particularly to FIGS. 2 and 3, there is illustrated a fragment of a cylindrical valve pot 12, which has been centrally bored, as at 11, of the type having its upwardly disposed end wall drilled, as at 16, for threadedly receiving stud bolts 18. The upper end 13 of the valve pot is counterbored, as at 15, for receiving a packing ring 17. The thickness of the packing ring 17 is normally greater than the depth of the counterbore 15. The above describes a conventional valve pot with which the present invention is to be used.

A cylindrical ring member 20, diametrically substantially equal with respect to the valve pot 12, replaces the conventional valve pot cover 14. The ring 20 has a relatively thick wall defining a central bore 22 of a size to freely receive a valve pot plug as hereinafter described. The wall of the ring is drilled, as at 24, for receiving the stud bolts 18. Nuts 26 hold the ring 20 in place. The ring 20 is counterbored from its downwardly disposed end, as viewed in FIG. 3, as at 28, forming a downwardly facing annular tapered shoulder 30.

25 A step diametered valve pot plug 40 is coaxially received by the bore 11 of the valve pot. The plug 40 includes a central body portion 42 having a circumferential wall closely received by the inner wall surface of the packing ring 17 and the wall forming the bore 11. The depending portion of the plug 40 is formed to define an inverted truncated cone 44. A depending internally threaded sleeve 46 is integrally formed coaxially on the depending end of the cone 44. A centrally bored valve stem receiving bushing 48 is threadedly received by the sleeve 46. The plug 40 is further characterized by an upper outstanding flange-like top or head end portion 50 diametrically slightly smaller than the ring bore 22 but greater than the diameter of the packing ring 17 so that a peripheral portion of the plug head 50 overlaps a portion of the valve pot end surface 13.

30 A stud bolt 54 is axially connected to the upwardly disposed end of the valve pot head 50. A plurality, preferably three, segmental wedge-shaped members 56 are positioned around the stud bolt 54. As shown in FIG. 3, the members 56 each have an outer end portion 58 terminating in an arcuate edge 59 complementary with but formed on a smaller radius with respect to the radius of the counterbore 28 so that the edge 59 does not contact the wall 28.

35 The lowermost surface 60 of the outer end portion 58 of each segment 56 flatly contacts the upper surface 62 of the head end portion 50 of the valve plug 40 while the lower surface of the other or inwardly directed end portion 70 of each segment is preferably positioned in spaced relation to the surface 62 in the manner explained hereinbelow. The end portion 58 of each respective segment is provided with an upper surface opposite the surface 60 formed on an angle or taper 64 complementary with respect to the tapered shoulder 30 for the purposes presently explained.

40 A centrally drilled substantially conical-shaped bushing 66 coaxially surrounds the bolt 54 and is held thereon by a nut 68. The end surface of the end portion 70 of each segment, opposite the outwardly disposed end 58, is arcuately curved on a radius and tapered for complementary contacting the tapered wall surface of the bushing 66 so that when the nut 68 is tightened the wedge members 56 are forced radially outward. A foot or support 72 is connected in depending relation to the lower surface of the respective inwardly directed end portion 70 of each segment 56 to maintain the tapered surface of each segment end portion in contiguous contact with

the surface of the bushing 66. Obviously the supports 72 can be omitted by a flat face to face contact between the wedges 56 and the plug surface 62.

Operation

In operation the ring 20 is connected to the valve pot 12 as disclosed hereinabove. The packing 17 is placed within the groove 15. The valve plug is positioned within the bore 11 on the packing 17. The segmental wedge members 56 are positioned, as shown in FIG. 3, and the nut 68 is tightened against the bushing 66 wherein the wedge surface 64 contacts the tapered shoulder 30 by the wedging action of the bushing 66 against the inwardly disposed ends of the segmental members, and forces the segments 56 radially outward toward the counterbore wall 28. This compresses the packing 17 by the contact of each wedge surface 60 against the valve plug surface 62. The degree or angle of the surfaces forming the above described cooperating tapered surfaces may be varied as desired to achieve the desired wedging action of the segments 56 in forcing the valve plug flange or head 50 against the packing ring 17 in sealing relation.

Referring now to FIG. 4, the numeral 12A indicates a fragment of a valve pot, identical with respect to the valve pot 12, which has been modified to receive the valve plug 40 and locking members 56. The valve pot 12A includes the threaded stud bolt receiving holes 16A but these holes 16A are not needed or used in this embodiment of the invention. This valve pot 12A is similarly provided with the bores 11A and 22A. The ring 20 is omitted. The wall forming the bore 22A is undercut to form a groove 28A, similar in form and in appearance with respect to the counterbore 28. The groove 28A forms a valve pot flange receiving seat or surface 13A similar to the surface 13 and a similar downwardly facing tapered shoulder 30A. The surface 13A is counterbored around the bore 11A for receiving a packing ring 17A. The valve plug 40 and locking members 56 may then be installed in the valve pot 12A in a manner similar to that described hereinabove for FIGS. 2 and 3. Obviously the valve pot 12A may be formed as described hereinabove during its manufacture for use with the plug 40 and wedge members 56.

Obviously the invention is susceptible to some change or alteration without defeating its practicability, and I therefore do not wish to be confined to the preferred embodiment shown in the drawings and described herein, further than I am limited by the scope of the appended claims.

I claim:

1. A valve cap for a slush pump of the type having an upwardly open valve pot, said valve pot having an upper end surface, comprising: a ring coaxially secured to the upwardly open end of said valve pot, said ring having an inner wall forming a downwardly facing annular shoulder adjacent its end surface opposite its connection with said valve pot; a valve plug supported by the upper end surface of said valve pot within said ring; a threaded bolt and nut axially connected with said valve plug and projecting beyond the end of said ring opposite its con-

nection with said valve pot; a conical bushing around said bolt; and lock means including a plurality of wedge-shaped segmental members extending radially outward from said bushing under said annular shoulder, said segmental members being wedged against said valve plug when said nut is tightened.

2. Structure as specified in claim 1 in which said segmental members are characterized by an arcuate outer end surface which is spaced inwardly from the inner wall of said ring and extends vertically between said annular shoulder and the adjacent surface of said valve plug, said segmental members having an arcuate opposite end surface contacting a peripheral portion of said bushing.

3. A valve cap for a slush pump of the type having an upwardly open valve pot, said valve pot having an upper end surface and having a circumferential series of threaded stud bolts and nuts connected to its upper end surface, comprising: a ring having a thickened wall, said thickened wall having a like series of apertures parallel with the axis of said ring for receiving said stud bolts, said ring having an inwardly and upwardly converging annular inner wall surface forming a downwardly facing tapered shoulder adjacent its end surface opposite its connection with said valve pot; a valve plug supported within said valve pot by said upper end surface; a threaded bolt and nut axially connected with said valve plug and projecting beyond the end of said ring opposite its connection with said valve pot; a conical bushing around said bolt; and lock means including a plurality of wedge-shaped segmental members extending radially from said bushing toward the inner wall of said ring, said segmental members being forced outwardly against said tapered shoulder and said valve plug when said nut is tightened.

35 4. A valve cap for a slush pump of the type having an upwardly open valve pot, said valve pot having a valve plug seat formed therein and having an inner wall forming an annular inwardly and downwardly facing shoulder opposite said seat, comprising: a valve plug supported by said seat; a threaded bolt and nut axially connected to said valve plug and projecting outwardly beyond the open end of said valve pot; a conical bushing surrounding said bolt; and lock means including a plurality of wedge-shaped segmental members extending radially outward from said bushing toward the inner wall of said valve pot below said annular shoulder, said segmental members forcing said valve plug against said seat when said nut is tightened.

50 5. Structure as specified in claim 4 in which said segmental members are characterized by an arcuate outer end surface terminating in spaced relation with respect to the inner wall of said valve pot, said segmental members each having an upper surface contacting said annular shoulder, said segmental members each having an arcuate opposite end surface contacting a peripheral portion of said bushing.
